UNITED STATES PATENT OFFICE.

JOHN E. DIMOND, OF BOSTON, MASSACHUSETTS, ASSIGNOR TO THE REECE
BUTTONHOLE MACHINE COMPANY, OF PORTLAND, MAINE, AND BOSTON,
MASSACHUSETTS.

BUTTONHOLE-SEWING MACHINE.

SPECIFICATION forming part of Letters Patent No. 718,103, dated January 13, 1903.

Application filed May 2, 1900. Serial No. 15,178. (No model.)

To all whom it may concern:

Be it known that I, JOHN E. DIMOND, a citizen of the United States, and a resident of Boston, county of Suffolk, and State of Massachusetts, have invented an Improvement in 5 Buttonhole-Sewing Machines, of which the following description, in connection with the accompanying drawings, is a specification, like characters on the drawings representing like parts.

This invention has for its object to provide a buttonhole-sewing machine of the class represented by United States Patent No. 494,280, dated March 28, 1893, with a pull-off, it operating after the completion of a buttonhole to pull off from the tension device a suitable amount of slack thread, the stitching mechanism having been stopped and being inactive, the pull-off retaining said thread until 15 the stitch-forming mechanism is started in the formation of another buttonhole, the pull-off giving up its thread to the first stitch, so that the first stitch in starting a buttonhole is unerringly caught in the material. To enable 20 the pull-off to act after the stitching mechanism has come to rest and take thread from the thread-supply, I have provided means for releasing the tension from the thread, the tension being released after the completion of 25 the buttonhole and before the pull-off acts, the thread connected with the last buttonhole stitched being cut off after pulling off thread sufficient to supply thread for the next buttonhole to be made.

30 Figure 1 represents in front elevation a sufficient portion of a sewing-machine of the class described to enable my invention to be understood, and Fig. 2 is a left-hand side elevation of the parts represented in Fig. 1.

35 Referring to the drawings, *a* represents part of the stitch-frame; *a'*, part of the clamp-frame; *b'*, the needle-bar, provided with an eye-pointed needle *b²*, it forming one member of a stitch-forming mechanism, the other 40 member in practice being an eye-pointed thread-carrying looper carried also by the stitch-frame, the said needle-bar and supplemental stitch-forming mechanism being all as fully illustrated in said patent, and in prac-

tice they are operated for stitching by means 50 provided for in said patent.

In the machine herein to be described, as in the machine represented in the patent, while the stitch-forming mechanism is operating to stitch about the buttonhole-slit the 55 stitch-frame is moved at one speed; but after the buttonhole has been completed a faster-speed driving mechanism is put automatically into operation to move the stitch-frame at a faster speed to bring a cutting mechanism, 60 fully illustrated in said patent and carried by the stitch-frame, into position with relation to the usual cloth-clamp common to that patent, that the cutting mechanism may be in a position to act after the operator has 65 removed from the clamp the material containing the stitched buttonhole and has put into the clamp the material to be cut and stitched to make a second buttonhole. Herein, as in said patent, the closing of the clamp 70 on the material in which the buttonhole is to be cut and stitched starts into operation the cutting mechanism, so that it immediately cuts the buttonhole in the fabric and at the same time the fast-speed driving mechanism 75 for the stitch-frame operates, putting the stitch-forming mechanism in the position to start the stitching of a buttonhole.

When the stitching of a buttonhole has been completed, the operation of the stitch-forming mechanism is automatically suspended and it remains in its inoperative position while the stitch-frame travels in its faster speed to put its cutter into proper co-operative relation with the usual anvil supporting 85 the under side of the material, and the stitch-forming mechanism remains inoperative until after the buttonhole has been cut and the stitch-forming mechanism has been returned into its starting or operative position for 90 stitching.

I have not deemed it necessary to show in the present drawings all the parts which will be used in this machine, the same being common to the patent referred to.

The upper portion or arm of the stitch-frame has erected upon it a stand 2, having at one side a hollow slotted projection or sleeve 3,

over which is fitted loosely a tension-wheel 4, one side of said tension-wheel being acted upon by a suitable disk 5, in turn acted upon by a spring 6, under the control of a nut 7, 5 the adjustment of the nut causing the spring to act against the disk with greater or less force to determine the proper amount of tension on the needle-thread. The sleeve and the hole in the stand receive a sliding stud 8, 10 having a head which meets a portion of the disk 5, standing in a slot of the sleeve. Whenever the sliding stud is acted upon positively at its outer end to slide the same in the sleeve, the pressure of the disk is removed from the 15 tension-wheel, leaving the thread without tension. This tension device, disk, and stud are substantially found in United States Patent No. 457,463, the stud in said patent being operated by a stationary cam. As herein shown, 20 I have provided the stand with a fulcrum 10, which sustains a pull-off 12, represented as an elbow-lever, having at its upper end an eye 13, which is slotted, as at 14, to enable the needle-thread 15 to be readily inserted in 25 said eye.

The stand 2 has a hole in which I have inserted the shank 16 of a thread-rest 17, represented as provided with shoulders 18, which sustain the thread when the needle-bar occupies its lowest position, said thread-rest having uprights between which the pull-off acts when pulling off thread from the tension device.

The take-up lever, herein numbered 19, is 35 in all particulars the same as the take-up used in United States Patent No. 494,280.

The stitch-frame has connected with it by screws 20 a frame 21, which in the best form of my invention presents two sets of guiding-sleeves 22 and 23, the sleeves 22 receiving a rod 24, represented as bent at its upper end and connected by a suitable stud-screw 25 with the short arm of the pull-off. A spring 26, surrounding the rod 24 and abutting 45 against one of the sleeves 22 and at its lower end against an adjustable collar 27, acts normally to keep the lower end of the rod 24 against a controlling-plate 28, suitably secured to the clamp-frame a' , said controlling-plate having an inclined or cam surface 29, (see dotted lines, Fig. 2,) which leads up to a support 30.

The pin 8 of the tension device, through the spring 6, acts against one end of a lever 55 34, pivotally mounted on the stand 2, and keeps the lower end of a rod 31 extended through the sleeves 23 to remain in contact with the upper side of the controller 28 at one side the surface 29. (Shown by dotted 60 lines.)

The drawings show the pull-off in its operative position and the needle elevated and at rest, the said needle and its co-operating stitch-forming mechanism having been stopped 65 when the last buttonhole was finished, the stitch-frame having been moved from the po-

sition it occupied when the last stitch in the buttonhole was made into its present position, this change of position of the stitch-frame putting the usual cutting mechanism, 70 the fulcrum 33 of which is shown in Fig. 2, in position to be started to cut the buttonhole whenever the usual clamp common to said patent, No. 494,280, is closed.

When the parts are in the position Fig. 2, 75 ready for the operator to close the clamp to start the machine to cut the buttonhole, it will be noticed that the lower ends of the rods 24 and 31 are sustained at the same level by the top 30 of the controller 28, and the tension is released and the pull-off is holding its supply of thread in a loop-form, as represented in Fig. 1 by dotted lines. As the stitch-frame travels backwardly or in the direction of the arrow 42, Fig. 2, after closing 80 the clamp and actuating the cutter to put the stitch-forming mechanism in the proper position with relation to the cut buttonhole to start the stitching, the rods 24 and 31 run down the inclines 29 to put the tension on 85 the thread and cause the pull-off to give up the slack thread to the needle, this being done just as the needle is ready to make its first thrust into the material in the starting of a buttonhole. Giving up the slack thread 90 to the needle at its first thrust enables the needle-thread to be unerringly caught when the first stitch is made, and thereafter during the further operation of stitching the buttonhole the lower ends of the rods 31 and 24 95 rest on the lower part of the controller 28, insuring the proper amount of tension on the thread, the upper end of the pull-off standing in its inoperative position substantially at the guide 17. As the stitching arrives at 100 the small end of the buttonhole the rods 24 and 31 are so acted upon in succession that after the last stitch in the buttonhole has been made and the stitch-forming mechanism has been put into its inoperative position 105 the tension device will be rendered inoperative, and the pull-off will be thrown into its operative position, as represented in the drawings, the tension remaining off and the pull-off holding its slack thread while the stitch-forming mechanism and cutter move into 110 proper position to cut a new buttonhole in cloth to be applied to the usual cloth-clamp. When the stitch-forming mechanism arrives 115 in this position, the operator cuts off the needle-thread close to the work and, as stated, the pull-off holds its thread, as shown in the drawings, and the tension is kept off from the thread until in the movement of the stitch-frame and stitch-forming mechanism into 120 starting position the stitch-forming mechanism is started into operation automatically, as provided for in said patent. At the first stitch made after starting the stitch-forming mechanism, the first stitch in the making of 125 a new buttonhole, the pull-off gives up its thread.

Having described my invention, what I claim as new, and desire to secure by Letters Patent, is—

1. In a buttonhole-stitching machine, the combination of a stitch-frame and a cloth-frame, a needle-bar having a needle, a tension device, a pull-off mounted on said stitch-frame and coacting with the needle-thread to pull the same through the tension device, a rod connected with said pull-off for operating the same, a cam carried by the cloth-frame to move said rod when the needle-bar is elevated and cause said pull-off to act and pull thread from the tension device.

15 2. In a buttonhole - stitching machine employing a stitch-frame and a cloth-frame, a needle-bar having a needle, a tension device, a pull-off mounted on said stitch-frame and coacting with the needle-thread, a rod connected with the said pull-off, a cam carried by said cloth-frame to engage the end of said rod and cause said pull-off to act and pull the thread from said tension device when the rod connected with said pull-off is raised by said

25 cam at a time when the needle-bar is elevated. 3. In a buttonhole-stitching machine, stitch-forming mechanism, a tension device acting normally on the needle-thread, a pull-off located between the needle-bar and tension device, rods connected with said pull-off and tension device, a cam coacting with the ends of said rods to move the same and release the tension on the needle-frame at a predetermined time and to thereafter immediately actuate the pull-off to provide slack thread for the needle while the needle-bar is at rest and preparatory to being started to stitch a second buttonhole.

4. In a sewing-machine, a cloth-frame, a needle-bar having an eye-pointed needle, a tension device, a pull-off engaging the needle-thread between the needle-bar and tension de-

vice, means operating to release the tension device to permit the pull-off to draw thread therethrough and to cause said pull-off to 45 draw thread from the tension device and hold it in the form of a loop while the needle-bar is elevated and the machine occupies its normal position of rest, the pull-off giving up the thread to be drawn through the eye of the 50 needle at the first descent of the needle-bar in making a first stitch said means including a cam carried by the said cloth-frame.

5. In a sewing-machine, a cloth-frame, a needle-bar having an eye-pointed needle, a 55 tension device, a pull-off engaging the needle-thread between the needle-bar and tension device, a support for the needle-thread, and means comprising a cam carried by the cloth-frame operating normally to release the tension device and also acting to cause said pull-off to draw thread from the tension device and hold it in the form of a loop while the needle-bar is elevated and the machine occupies its normal position of rest, the pull-off 60 giving up the thread to be drawn through the eye of the needle at the first descent of the needle-bar in making a first stitch.

6. In a sewing-machine, the combination of a stitch-frame and a cloth-frame, a needle-bar 70 having a needle, a tension device, a pull-off mounted on said stitch-frame, a rod for releasing the tension device, a rod connected with said pull-off, a cam carried by the cloth-frame to engage and move each of said rods 75 to release the tension device and pull thread therethrough.

In testimony whereof I have signed my name to this specification in the presence of two subscribing witnesses.

JOHN E. DIMOND.
